UNITED STATES PATENT OFFICE.

FRANK H. ENGSTROM, OF CAMBRIDGE SPRINGS, PENNSYLVANIA.

DESIGN FOR A WRENCH.

SPECIFICATION forming part of Design No. 34,540, dated May 21, 1901.

Application filed April 15, 1901. Serial No. 56,013. Term of patent 7 years.

To all whom it may concern:

Be it known that I, FRANK H. ENGSTROM, a citizen of the United States, residing at Cambridge Springs, in the county of Crawford and 5 State of Pennsylvania, have invented and produced a new and useful Design for Wrenches; and I do hereby declare the following to be a full, clear, and exact description of the invention, such as will enable others skilled in o the art to which it appertains to make and use the same.

In the drawings, Figure 1 is a side view of the wrench. Fig. 2 is a plan view of the wrench. Fig. 3 is a cross-section through the 5 sockets of the wrench. Fig. 4 is a cross-section through the handle.

The leading or material features of the design consist of a circular head containing at one end a large hexagonal socket, an octagonal socket at its other end of smaller size than the large socket and tapered at one end where it joins onto the large socket, and a

handle having a cylindrical end portion and a portion oval in cross-section and joining the cylindrical portion to the said head. 25

A is the circular head.

B is the large hexagonal socket.

C is the octagonal socket, which is smaller than the socket B and which has a tapering portion c at one end where it joins onto the 30 socket C.

D is the cylindrical end portion of the handle, and d is the portion of the handle which is oval in cross-section and which joins the portion D to the head A. 35

What I claim is—

The design for a wrench, as herein shown and described.

In testimony whereof I affix my signature in presence of two witnesses.

FRANK H. ENGSTROM.

Witnesses:

JOHN D. GAGE,
J. K. GAGE.
